UNITED STATES PATENT OFFICE.

ALLAN B. CAMERON, OF WILLIAMSPORT, PENNSYLVANIA.

DESIGN FOR A PANEL.

SPECIFICATION forming part of Design No. 19,590, dated January 21, 1890.

Application filed December 28, 1889. Serial No. 335,272. Term of patent 14 years.

To all whom it may concern:

Be it known that I, ALLAN B. CAMERON, of Williamsport, Lycoming county, Pennsylvania, have invented and produced a new and original Design for Panels, of which the following is a specification, reference being had to the accompanying photograph, forming part hereof.

Upon the surface of the panel appear lenticular elevations A B C D. Between each pair of said elevations, as A and B, B and C, C and D, appear two sets of triangular elevations, four elevations being in each set. Between A and B appear the elevations 1 2 3 4 and 5 6 7 8. Between B and C appear the elevations 9 10 11 12, 13 14 15 16. Between D and E appear the elevations 17 18 19 20, 21 22 23 24. Between the set of elevations marked 1 2 3 4 and the set of elevations marked 9 10 11 12 appears a set of three elevations marked 25 26 27. Between the elevations marked 9 10 11 12 and the elevations marked 17 18 19

20 appears a set of three elevations marked 28 29 30. Between the elevations marked 5 6 7 8 and the elevations marked 13 14 15 16 appears a set of three elevations marked 31 32 33. Between the elevations marked 13 14 15 16 and the elevations marked 21 22 23 24 appears a set of three elevations marked 34 35 36. Finally, between the set of three elevations marked, respectively, 25 26 27 and 28 29 30 appears a pair of triangular elevations 37 38, and between the sets of elevations marked 30 31 32 and 33 34 35 appears a pair of elevations marked 39 40. The entire group of elevations above named shows a circular outline.

I claim—

The design for an ornamental panel, substantially as herein shown and described.

ALLAN B. CAMERON.
